UNITED STATES PATENT OFFICE.

CHARLES L. HOLDEN, OF INDIANAPOLIS, INDIANA.

HEATING APPARATUS FOR HOT-WATER BOILERS.

SPECIFICATION forming part of Letters Patent No. 576,313, dated February 2, 1897.

Application filed February 11, 1896. Serial No. 578,911. (No model.)

To all whom it may concern:

Be it known that I, CHARLES L. HOLDEN, a citizen of the United States, residing at Indianapolis, in the county of Marion and State 5 of Indiana, have invented certain new and useful Improvements in Heating Apparatus for Hot-Water Boilers, of which the following is a specification.

My invention relates to that class of devices 10 commonly known as "hot-water" boilers, which are mostly employed in domestic use; and it consists especially in an improved heating apparatus therefor.

Said invention will be first fully described, 15 and the novel features thereof then pointed out in the claims.

Referring to the accompanying drawings, which are made a part hereof and on which similar letters and numerals of reference indicate similar parts, Figure 1 is a vertical 20 sectional view of a hot-water boiler and the immediately adjacent parts, including the heating apparatus embodying my present invention, and Fig. 2 a horizontal sectional 25 view through said heating apparatus on an enlarged scale.

In said drawings the portions marked A represent the boiler proper or tank; B, the heating-chamber; C, the burner, and D a hood 30 or casing for the heating-chamber and forming a combustion-chamber.

The tank, or "boiler," as it is usually termed, is or may be of any usual or desired construction. It is provided with the cold-water-ingress pipe 1 and the hot-water-egress pipe 2, which usually enter at the top. Circulating-pipes 3 and 4 connect this tank with the heating-chamber B, as shown, the pipe 3 leading from the bottom of the tank A to near 35 the bottom of the chamber B, and the pipe 4 leading from the top of the chamber B back into the tank A at any desired point higher up, so as to maintain a circulation.

The heating-chamber B is of a peculiar form 40 and construction. It should be tapered, as shown, with the larger end upward when in position for use and decrease in size regularly toward the bottom, where it is provided with a screw-threaded bushing b, forming the 45 bottom, and to which a discharge-cock B' is secured. As before stated, the pipe 3 enters this chamber at a point above its bottom, so

as to leave a space below into which sediment may settle, which may be discharged through said cock B'. Should the sediment become 55 caked or solid in any way, the bushing b can be readily removed, which, being substantially the full size of the lower end, leaves an orifice large enough to easily remove any obstruction that may form. As the extreme 60 lower end is always covered with water and generally with sediment, and as the ingress-pipe and burner are located above this point, there is no danger of the parts becoming fastened together by the action of the heat, 65 while the sediment, not being subject to the direct action of the heat, remains in a soft or loose condition and is easily discharged, whereas when such sediment comes directly 70 against a part the opposite surface of which is exposed to flame it, as is well known, becomes baked and hard and covered with lime or similar incrustation.

The burner C surrounds the chamber B and is formed to discharge the fuel-gas directly 75 against the surface of said chamber, and the flame rises along the outer walls of said chamber toward the top, hugging it closely the entire length, the latter result being aided by the flaring exterior of said chamber. A maximum result for the amount of heat employed 80 is thus secured. The gas or other fluid fuel is supplied through the pipe C'.

The hood or casing D incloses that portion of the chamber B above the burner C, and its 85 lower edge is shown as resting upon said burner, making a comparatively tight combustion-chamber; but this contact is not essential, as the casing may be of a different form and differently supported without departing from my invention. A tube or pipe D' leads from the upper end of this casing D and preferably connects with a flue of the building, so as to carry off the fumes or products of combustion. 90

The operation is as follows: The water enters the tank A through the pipe 1 and is preferably carried thereby nearly to the lower end of said tank, as is usual. From the bottom of said tank it flows into the chamber 95 B through the pipe 3 and is there effectually heated by the flames from the burner C, which are driven against the exterior of said chamber. It then returns to the tank A through 100

the pipe 4 and rises to the top, whence it may be drawn off through the pipe 2. The fuel, preferably gas, enters the burner C from any convenient source of supply through the pipe 5 C', and being ignited the resulting flame impinges against and closely hugs the exterior surface of the heater B. Said burner and the upper portion of the chamber being inclosed by the casing D the fumes and products of combustion are confined and prevented from escaping into the building. When it is desired to clean out the accumulated sediment, it is ordinarily only necessary to open the cock B', for reasons already stated; but if through carelessness or inattention the sediment is allowed to become hard or bulky it can always easily be removed by unscrewing the bushing b.

Having thus fully described my said invention, what I claim as new, and desire to secure by Letters Patent, is—

1. The combination, with a water-boiler, of a separate heating apparatus consisting of a chamber, circulating-pipes connecting said boiler and said chamber, and a burner surrounding said chamber at a point some distance above its lower end, whereby the lower

end below said burner may serve as a settling-chamber and not be in direct contact with the fire, substantially as described and 30 for the purposes specified.

2. The combination with a boiler of a heating apparatus consisting of a chamber, a heater above the lower end of same, circulation-pipes connecting said boiler and chamber, the pipe leading into said chamber being connected therewith below said heater, substantially as set forth.

3. The combination with a boiler of a heating apparatus consisting of a tapered heating- 40 chamber arranged with its large end upward, its lower end forming a settling-chamber with discharge devices, a burner surrounding said chamber above said lower end, and circulation-pipes connecting said boiler and chamber, substantially as set forth.

In witness whereof I have hereunto set my hand and seal, at Indianapolis, Indiana, this 8th day of February, A. D. 1896.

CHARLES L. HOLDEN. [L. S.]
